UNITED STATES PATENT OFFICE.

REX SCHAFER, OF LONG BEACH, CALIFORNIA.

AMUSEMENT DEVICE.

Application filed October 5, 1923. Serial No. 666,777.

To all whom it may concern:

Be it known that I, REX SCHAFER, a subject of the King of Great Britain, residing at Long Beach, in the county of Los Angeles and State of California, have invented certain new and useful Improvements in an Amusement Device, of which the following is a specification.

This invention relates to amusement devices and the primary object of the invention is to provide a novel device for amusement parks, which will provide a maximum amount of pleasure for the patrons thereof.

Another object of the invention is to provide a device for amusement parks comprising an endless flexible train or carrier upon which persons are adapted to sit arranged to travel around a tortuous course disposed either in a horizontal or inclined plane, the tortuous course embodying a plurality of relatively short turns or curves giving the carrier or train a pleasing and novel movement.

A further object of the invention is to provide a novel endless train or carrier arranged to travel about an endless course having constructed thereon different figures, simulating various kinds of animals and reptiles, the figures having secured thereto saddles or seats upon which the patrons of the amusement device are adapted to sit.

A further object of the invention is to provide an amusement device of the above character, that is flexible in construction and so arranged as to safely carry a load and at the same time provide fun and amusement for persons carried by the structure, the mechanism providing amusement to persons viewing the device.

A further object of the invention is to provide an amusement device of the character stated embodying a plurality of trucks, and novel means for binding the trucks together, to permit the same to follow the tortuous course over which the carrier is adapted to travel, the trucks having resiliently connected therewith the body of a figure on which the persons are adapted to ride.

A further object of the invention is to provide novel means for incorporating a power unit in one of said trucks to bring about the propelling of the carrier over and around the tortuous course.

A further object of the invention is to provide a novel king pin structure carried by each truck forming a spindle for horizontally disposed guide rollers and a bearing for a horizontally disposed shaft for supporting vertical wheels for helping to sustain the load of the trucks, the novel king pin structures also forming means for flexibly binding the trucks together.

A further object of the invention is to provide novel supporting members for the trucks for engaging a hidden track for helping to sustain the load and novel means for connecting the supporting members with the truck and with one another.

A further object of the invention is to provide a novel pony truck carried by the leading supporting truck to form a guide therefor, to eliminate any tendency of the trucks to sway out of a given line or path.

A still further object of the invention is to provide a novel amusement device of the above character, which will be durable and efficient in use, one that will be comparatively simple and easy to manufacture and one which can be placed upon the market at a reasonable cost.

With these and other objects in view, the invention consists in the novel construction, arrangement and formation of parts, as will be hereinafter more specifically described, claimed and illustrated in the accompanying drawings, in which drawings:

Figure 1 is a longitudinal fragmentary section through a portion of the amusement device illustrating the formation of the power or propelling truck.

Figure 2 is a fragmentary longitudinal section through a portion of the device taken directly in rear of Figure 1 and illustrating the construction of the trailing trucks arranged in rear of the propelling or power trucks.

Figure 3 is a fragmentary plan view partly in section of one of the figures connected with the trucks.

Figure 4 is a fragmentary horizontal section through a pair of the trailing trucks.

Figure 5 is an enlarged horizontal section through the driving or propelling trucks.

Figure 6 is a detail vertical section taken on the line 6—6 of Figure 2 illustrating one of the trailing trucks.

Figure 7 is a detail section taken on the line 7—7 of Figure 2 illustrating the novel king pin.

Figure 8 is a diagrammatic view in plan showing the arrangement of the guiding sheaves or drums which form the tortuous way or course for the carrier.

Figure 9 is an enlarged vertical section through the floor of the amusement device illustrating one of the guiding drums or sheaves in detail.

Figure 10 is an enlarged longitudinal section through one of the guiding cables illustrating the novel take-up therein.

Referring to the drawings in detail, wherein similar reference characters designate corresponding parts throughout the several views, the letter A generally indicates the improved amusement device as an entirety, which includes the supporting base B and the endless carrier C.

The supporting device B comprises a floor 15 which may be disposed in a horizontal plane or in an inclined plane. As shown the floor 15 is arranged in a horizontal plane and is provided with a tortuous slot or a guideway 16, the purpose of which, will be hereinafter more fully described. This floor 15 can be supported by suitable beams 17 held in position by posts or standards 18. These standards 18 can rest directly upon the ground, a concrete base, or beams 19 which are also utilized for supporting a horizontally disposed guide track 20, which is arranged directly below and in alignment with the slot or guideway 16 formed in the floor 15.

Arranged directly below the floor 15 are disposed spaced guide drums 25 and these guide drums are arranged at advantageous points around the tortuous guideway or slot 16 formed in the floor. Each drum 25 comprises a circular body 26 which supports upper and lower relatively large guide sheave wheels 27, which are bolted as at 28 to the upper and lower surfaces of the body. The upper and lower sheaves 27 are adapted to receive and form guides for upper and lower flexible cables 40 and 41 which form a part of the carrier B, which will be hereinafter more fully described. These drums 25 are rotatably mounted upon suitable shafts 29 which can rest in suitable bearings carried by the drums. The shafts 29 can be secured in any preferred way to the

floor 15 or beams 19. It is obvious that the drums can be positively rotated and thus act as driving means for the upper and lower cables 40 and 41. However, means which will be more fully described hereinafter, is provided for positively driving the carrier C over the floor and around the tortuous guideway defined by the slot 16 in the floor.

The terminals of the cables 40 and 41 can be connected to novel devices for permitting any slack to be taken up therein and as shown Figure 10, a sleeve 30 is provided for each cable terminal and this sleeve can be rigidly secured to any preferred portion of the carrier C. The sleeve 30 is provided with internal threads 31 and receives an adjusting nut 32, which is adapted to bear against a head 33 slidably mounted in the sleeve. This head is secured to the cable terminal in any desired way. It can be seen that by threading the nut 32 into and out of the sleeve 30 that the tension of the cable can be readily regulated.

The carrier B comprises any preferred number of figures 45 which are constructed to simulate various animals, reptiles and the like and these figures are secured by means, which will be hereinafter more fully described, at spaced points to the cables 40 and 41.

Each figure 45 comprises a pair of leading trucks 46 and 47, which also constitute the propelling portions of the carrier and a plurality of trailing trucks 48. The trucks 46, 47, and 48 are all constructed along the same principle, and as shown, the leading trucks 46 and 47 comprise upper and lower supporting blocks 49 and 50, which are connected together in spaced relation by means of a connecting strap 51, which is bent around the blocks to closely embrace the same. If desired the strap 51 can be bolted to the blocks 49 and 50. The terminals of the strap 51 are extended above the block 49 and arranged in abutting relation to form a supporting standard 52 and at the extreme upper end of the standard 52 the strap ends are bent outwardly to provide attaching and supporting ears 53.

The truck 46 carries a vertically disposed king pin 54, which is rotatably mounted in the lower block 50 and this king pin is provided with a head 55, which is rotatably mounted in the upper block 49. The upper block 49 is suitably recessed to receive the head 55 and slotted as at 56 which communicates with the recess for receiving the forward end of a connecting rod 57, which is utilized to connect the truck 46 with the first trailing truck 48. The head 55 of the king pin 54 rockably supports a nut 58 for swinging movement in a horizontal plane and this nut receives the forward end of the connecting rod 57 and by this construction

it can be seen that the connecting rod 57 is free in a horizontal and vertical plane to permit the binding of the trucks together for swinging movement. Arranged above 5 the block 49 is a suitable bearing block 59, which can be secured to the strap 51 and this bearing block 59 rotatably supports a transverse axle 60 the terminals of which are keyed to drive wheels 61. The drive 10 wheels 61 engage the floor 15 on opposite sides of the slot 16 and the floor can be provided with suitable tracks 14. Figures 5 and 6.

The shaft 60 has keyed or otherwise secured thereto a drive beveled gear wheel 62, which has meshing therewith a bevel pinion 63, keyed or otherwise secured to the armature shaft 64. A suitable bearing 15 66 is also carried by the strap 51 for supporting the armature shaft 64 and the electric motor 65 can be mounted upon a platform 67, which can be carried by the connecting rod 68 utilized for connecting the truck 46 with the truck 47. As 20 clearly shown, in Figure 1 of the drawings, the connecting rod 68 is connected by means of a pivot bolt 69 with a pair of rigid angle brackets 70, which are bolted or otherwise secured to the strap 51. The connecting rod 25 68 is similar to the connecting rod 57, with the exception that the forward end thereof is set upwardly and forwardly, as can be clearly seen by referring to the drawings. The forward end of the connecting rod 68 is 30 connected to a king pin 71 which is of the same type as the king pin 54 carried by the truck 46 and the connecting rod is connected in the same manner to the king pin 71 as the connecting rod 57 is connected to the king 35 pin 54. It can also be seen that the king pin is supported by upper and lower blocks 72 and 73 which are of the same construction as the upper and lower blocks 49 and 50 of the truck 46. The blocks 72 and 73 are also 40 held together by means of a strap 74 which is identically the same construction as the strap 51. The strap 74 also carries a bearing 75 for the transverse axle 76 which carries floor engaging wheels 77, which correspond to the floor engaging drive wheels 61. Each of the king pins 54 and 71 have rotatably mounted thereon a guide wheel 78 and these guide wheels 78 are arranged in a horizontal plane and engage the walls of the slot 45 16 formed in the floor, and permit the figure to follow the curvatures of the slot. Each of the lower blocks 50 and 73 also carries a transverse axle 79, the terminals of which carry wheels 80 which are adapted to engage 50 the lower surface of the floor on each side of the slot 16 and suitable tracks can be provided for these wheels if so desired.

In order to bring about the supplying of current to the motor 65, a depending trolley arm 81 is carried by the connecting rod 68

and this depending trolley arm 81 is deflected laterally and rotatably supports a trolley wheel 82, which is adapted to engage suitable electric conducting wire 83. The current collected by the wheel 82 can be 70 transmitted to the motor 65 in any preferred way.

In order to prevent the forward tipping of the figures a leading or feeler truck 85 can be provided, which embodies a bracket 75 86 arranged to extend directly in the slot 16 of the floor 15 and this bracket 86 is bolted or otherwise secured as at 87 to the forward end of the truck 47. This bracket 86 rotatably supports a vertically disposed axle 88 on which is mounted a guide wheel 89, which is so constructed as to engage the opposite walls of the slot 16. The bracket 86 also carries upper and lower axles 90 and 91, the terminals of which carry guide and supporting wheels 92 which engage respectively the upper and lower surfaces of the floor on each side of the guideway or slot 16. Thus it can be seen that not only are the trucks themselves, provided with novel means for engaging the walls of the slots and means for engaging the upper and lower surfaces of the floor on each side of the slot, but also means of arranging the advance of the trucks for engaging the walls of the slot and the upper and lower surfaces of the floor to prevent tipping of the forward end of the figures.

The trailing trucks 48 are all of substantially the same construction, and thus only 100 one will be described in detail.

Each of the trucks 48 comprises upper and lower blocks 95 and 96 which are arranged in spaced relation to one another and held in place by means of a loop portion 97 of the holding strap 98. This strap 98 is identical in construction with the straps 51 and 74 of the trucks 46 and 47. The strap for the loop portion 97 is extended to form a supporting arm 99, and the terminals of the strap are bent at right angles to provide attaching lugs or ears 100. Now it can be noticed at this point, that the arms 99 of the trucks 48 and the arms 52 of the trucks 46 and 47 can be extended different distances above the truck to conform to different curvatures of the backs of the animals or figures, as will become hereinafter more fully apparent. The blocks 95 and 96 rotatably support a king pin 101 which is identical in construction with the king pins 54 and 71 and these king pins rockably receive the connecting rods 102 at the forward ends of the connecting rods 102, which are utilized for connecting the trailing trucks together. It is to be also noted that the connecting rod 57 which has its forward end supported by the king pin 54 is connected to the forward leading truck 48 by means of a pivot bolt 104 to 110 angle brackets 105 rigidly connected to the 115

said truck. The rear terminals of all of the connecting rods 102 are connected by means of pivot bolts 106 with angle brackets 107 carried by the forward faces of the trucks 48. All of the king pins 101 carry suitable horizontally disposed wheels 108 for engaging the opposite walls of the slot 16 in the floor 15. The upper and lower blocks 95 and 96 support suitable axles 109 and 110, the terminals of which carry the floor engaging wheels 111 and 112 respectively and these wheels of course engage the opposite surfaces of the floor.

All of the trucks 48, 46 and 47 carry suitable supporting and propelling posts or standards 115, which form means for binding the trucks to the cables 40 and 41. Now if so desired the lower surfaces of the trucks can carry U-shaped loops 116 in lieu of the propelling or the supporting standards 115 to permit suspension carriages of the type shown in my prior Patent #1,447,895 dated March 6, 1923 to be connected therewith. Each of these standards 115 is connected by suitable means to the trucks and can be made in sections to facilitate the positioning thereof around the cables 40 and 41, which they are adapted to embrace. The lower terminals of each standard 115 is bifurcated to form a yoke 117 which carries an axle 118 on which is rotatably mounted a supporting guide wheel 119 which is adapted to engage the lower track 20 heretofore mentioned. The portions of each standard 115 through which the cables 40 and 41 extend are enlarged as at 120 and the standards are slotted above the enlarged portions as at 121 and this slotted portion receives adjusting nuts 122 in which is threaded a stem 123. This stem engages a cable gripping head 124 and forms means for rigidly binding the standards to the cables.

It is also desirable to flexibly bind the standards 115 together in order to add rigidity to the figures and as shown, the opposite faces of the standards are provided with pivot ears 125 which are adapted to engage pivot ears 126 formed on connecting links or blocks 127. Suitable hinge pins 128 extend through the ears 125 and 126.

A relatively heavy cable 130 is connected to the attaching ears or lugs 100 of the truck 48 and to the ears 53 of the trucks 46 and 47 and these cables 130 form the backbone of the figure. The body of each figure also embodies supporting ribs 131 which can be made of resilient material if so desired. As shown these ribs 131 are in the nature of substantially circular-shaped open bands and the terminals of the bands are bolted or otherwise secured to any preferred part of the trucks. It is to be understood of course that the intermediate ribs 131 which are arranged between the trucks are to be

bolted or otherwise secured to the connecting rods 102, 67 and 68. The ribs 131 are now covered with any kind of material to form a skin 133 for the figure and the skin of course is shaded so as to simulate the appearance of the animal, which the figures are to simulate. Any number of seats or saddles 135 are arranged upon the figures and these seats are arranged directly above the arms 99 and can be secured thereto if so desired.

Now from the foregoing it can be seen that I have provided a novel and simple amusement appliance, which will form a maximum amount of pleasure for the patrons of an amusement park which will be attended by a minimum amount of danger. It is to be noted however, that the appearance of the device is novel and that the same will give the effect of being crowded with dangerous curves, which will excite the patrons. Owing to the means of binding the trucks together the figures can take relatively short curves and when the device is in operation, the figures will give the appearance of darting quickly in and out around the floor.

Changes in details may be made without departing from the spirit or the scope of this invention.

What I claim as new is:

1. In an amusement device, a tortuous guideway, endless cables arranged to travel about the guideway, figures arranged at spaced points on and secured to the cables, each of the figures including a plurality of independent trucks and means for flexibly connecting the trucks together.

2. In an amusement device, an endless tortuous guideway, an endless cable, means for guiding the cable about the guideway, a plurality of figures arranged to simulate the appearance of animals secured to the cable, each of the figures including independent trucks, means flexibly binding the trucks together, and guide wheels carried by the trucks for engaging the guideway.

3. In an amusement device, a tortuous endless guideway, an endless cable, means for training the cable about the guideway, figures simulating the appearance of creatures of the air, sea and land connected to the cables, each of the figures including a plurality of flexibly connected trucks, guide wheels carried by certain of the trucks for engaging the guideway, propelling wheels carried by certain other of the trucks for engaging the guideway, and means for operating the propelling wheels.

4. In an amusement device of the character described, an endless tortuous guideway, an endless cable, means for training the cable about the guideway for traveling movement around the guideway, a plurality of figures carried by the cable, each of the fig-

- ures including flexibly connected trucks, guide wheels carried by the trucks for engaging the guideway, a longitudinally extending flexible member connected to the 5 upper terminals of the trucks for forming a backbone for the figure, resilient ribs connected to the backbone and to the trucks for supporting the backbone, and a covering secured to the backbone and ribs.
- 10 5. In an amusement device of the character described, a floor having an endless tortuous guide slot therein, a track arranged below the floor in direct alignment with the tortuous guide slot, endless cables arranged 15 between the floor and track, means for guiding the cables about the tortuous slot and track, a plurality of figures, seats arranged on the figures, each of the figures including a plurality of trucks, means for binding 20 the trucks together, depending supporting standards connected with the lower ends of the trucks, rollers carried by the standards for engaging the track, means carried by the standards for gripping the cables and guide 25 rollers carried by the tracks for engaging the floor and of the guide slot.
6. In an amusement device, a floor having an endless tortuous guide slot therein, a track of tortuous formation arranged below the floor in alignment with the tortuous 30 guide slot, guiding means arranged at predetermined spaced points around the guide slot below the floor, endless flexible cables trained about said guiding means arranged 35 to follow the curvatures of the guide slot and track, figures arranged at spaced points on the cables each including a plurality of independent trucks, means for binding the trucks together, wheels carried by the trucks 40 for engaging the floor and walls of the slot, depending supporting standards carried by the trucks, a rotatable guide wheel carried by the lower end of each standard for engaging the track, cable gripping means carried 45 by each standard for engaging the cable, and links connecting the standards together.
7. In an amusement device, a floor having an endless tortuous guide slot therein, rotatable drums disposed in spaced relation to the floor and arranged around the guide slot at spaced points, each of the drums including upper and lower guide sheaves, upper and lower endless cables trained around the 50 outer surface of certain of the sheaves and around the inner surface of certain other of the sheaves, flexible figures secured to the cables and seats on the figures.
8. In an amusement device, a floor having 55 an endless tortuous guide slot therein, a track disposed below the floor in alignment with the guide slot, a plurality of rotatable drums arranged between the track and the floor disposed at spaced points around the 60 guide slot, flexible cables trained about the 65 outer surface of certain of the drums and the inner surface of certain other of the drums, a plurality of flexible figures, depending standards extending through the guide slot, rollers carried by the lower ends of the standards for engaging the track, guide rollers carried by the figures for engaging the upper and lower surface of the floor and the walls of the guide slot, and cable gripping means carried by the standards for binding the standards to the cables. 70
9. In an amusement device, a figure including a plurality of trucks, means flexibly connecting the trucks together, spaced axles carried by the trucks, spacing wheels carried 80 by the axles, a vertically disposed axle, and a horizontally disposed roller carried by the axle and arranged between the spacing rollers.
10. In an amusement device, a flexible figure including a plurality of trucks, a rotatable king pin carried by each truck, a horizontally disposed roller mounted upon the king pin, a head formed on the upper end of the king pin, a rockable block carried by the head of the king pin, a connecting rod secured to the rockable block, the connecting rod extending rearwardly from the king pin, and means carried by the next adjacent truck for receiving the connecting 90 rod. 85
11. In an amusement device, a flexible figure including a plurality of trucks, each of the trucks including a frame, a pair of spaced blocks connected to the frame, horizontally disposed axles carried by the blocks, wheels mounted upon the axles arranged in a vertical plane and in alignment with one another, a rotatable king pin carried by the axial center of the blocks and a horizontally disposed roller carried by the king pin and arranged between the blocks and the first mentioned rollers. 100
12. In an amusement device, a flexible figure including a pair of propelling trucks and a plurality of trailing trucks, means for flexibly binding all of the trucks together, guide wheels carried by the trailing trucks, propelling wheels carried by the propelling trucks, a motor, and means connecting the propelling wheels with the trailing trucks. 105
13. In an amusement device, a flexible figure including a pair of propelling trucks and a plurality of trailing trucks, means for flexibly binding all of the trucks together, guide wheels carried by the trailing trucks, propelling wheels carried by one of the propelling trucks, a motor bed carried by the propelling trucks, an electric motor arranged on the bed, means operatively connecting the motor with the propelling wheels, and a trolley wheel carried by the propelling trucks for engaging an electric cable. 115
14. In an amusement device, a flexible figure including a pair of propelling trucks and a plurality of trailing trucks, means for flexibly binding all of the trucks together, guide wheels carried by the trailing trucks, propelling wheels carried by one of the propelling trucks, a motor bed carried by the propelling trucks, an electric motor arranged on the bed, means operatively connecting the motor with the propelling wheels, and a trolley wheel carried by the propelling trucks for engaging an electric cable. 120
15. In an amusement device, a flexible figure including a pair of propelling trucks and a plurality of trailing trucks, means for flexibly binding all of the trucks together, guide wheels carried by the trailing trucks, propelling wheels carried by one of the propelling trucks, a motor bed carried by the propelling trucks, an electric motor arranged on the bed, means operatively connecting the motor with the propelling wheels, and a trolley wheel carried by the propelling trucks for engaging an electric cable. 125
16. In an amusement device, a flexible figure including a pair of propelling trucks and a plurality of trailing trucks, means for flexibly binding all of the trucks together, guide wheels carried by the trailing trucks, propelling wheels carried by one of the propelling trucks, a motor bed carried by the propelling trucks, an electric motor arranged on the bed, means operatively connecting the motor with the propelling wheels, and a trolley wheel carried by the propelling trucks for engaging an electric cable. 130

14. In an amusement device, a tortuous guideway, a figure arranged to travel around the tortuous guideway including a pair of propelling trucks and a plurality of trailing trucks, means for flexibly connecting the trucks together, propelling means carried by the propelling trucks, guide wheels carried by all of the trucks for engaging the tortuous guideway, and a leading guide truck car-

ried by the forward propelling truck and 10 horizontally vertically disposed wheel carriages carried by the leading truck.

In testimony whereof I affix my signature in presence of two witnesses.

REX SCHAFER.
